William Elvist
ATTORNEY

UNITED STATES PATENT OFFICE

GODFREY DALKOWITZ, OF NEW YORK, N. Y., ASSIGNOR TO AMERICAN SAFETY RAZOR CORPORATION, OF BROOKLYN, NEW YORK, A CORPORATION OF VIRGINIA

RAZOR

Application filed October 15, 1927. Serial No. 226,299.

My present invention relates generally to razors, and has particular reference to a safety razor holder wherein a blade seat is associated with a pivotally mounted cover therefor.

It is an object generally of my invention to simplify the employment of such a holder, and to this end, to provide a device which is simple of construction and provided with features of operation which greatly facilitate handling and employment thereof.

More particularly, it is an object of my invention to provide a holder wherein certain structural features greatly simplify the operations of opening and closing the cover with respect to the blade seat. As is well known, these operations must be performed each time the holder is employed, so that the blade may be cleaned, or changed.

It is another object of my invention to provide means which will increase the certainty that the blade employed will assume a proper positioning upon the seat; the means which I have devised being of an extremely simple yet efficient character, and serving an additional function in connection with the before-mentioned simplified opening and closing of the cover.

One feature of my invention lies in providing spring means which are so arranged as to (1) yieldably retain the cover in closed position, (2) yieldably bear against the blade to position it properly with respect to the blade seat, and (3) fulfill these functions simultaneously and in a cooperative manner whereby opening of the cover and simultaneous release of pressure upon the blade may be effected by the simple manipulation of a single element or tab.

More particularly, it is a feature to provide an element which is so constructed and arranged as to be serviceable both as a blade-pressing element and also as a cover-opening element. A particular feature of the invention resides in an arrangement whereby this element and the cover are mutually cooperative; so that (a) closing of the cover will initiate the operation of said element as a blade-pressing element, and so that, reciprocally, (b) release of said element from the

blade will initiate a re-opening of the cover.

A further feature of the invention lies in providing spring means for yieldably retaining said element in either one or the other of its positions, i. e., either forwardly against 55 the blade, or rearwardly away from the blade. In this way, manipulation of a single simple tab will serve, by merely initiating the rearward movement of said element, to effect not only a full release of the blade by 60 said element but also a full re-opening of the cover.

For the attainment of the foregoing objects and such other objects as may hereinafter appear or be pointed out, I have illustrated two 65 forms of my invention in the accompanying drawings, in which—

Fig. 1 is a perspective view, looking diagonally upwardly, of a razor holder embodying the features of my invention; 70

Fig. 2 is a plan view of the blade seat with the cover thrown back;

Fig. 3 is a bottom view of Figure 2, with the upper portion of the handle omitted and the seat-supporting platform broken away; 75

Fig. 4 is a fragmentary cross-sectional view taken substantially along the line 4—4 of Figure 3 and showing the cover in closed and substantially opened positions;

Fig. 5 is a view similar to Figure 4 taken 80 substantially along the line 5—5 of Figure 3, similarly showing the cover in two positions and showing also the blade-pressing element in two corresponding positions;

Fig. 6 is a diagonally downward perspective view of the seat-supporting platform which has been broken away in Figure 3, and which has associated therewith the blade-pressing element; and 85

Fig. 7 is a view similar to Figure 5 showing a modified form of construction.

Referring to Figure 1, 10 represents the usual handle upon which is mounted a blade seat 11 having the usual forward guard 12. Between the handle 10 and the blade seat 11 is a blade seat support or platform 13 whose structure will be described in greater detail hereinafter. Pivotally associated with the blade seat 11 is the cover 14.

In Figure 2 I have shown how the cover 100

14 is pivoted to the blade seat 11, two loops or bearings 15 extending rearwardly from the opposite corners of the rear edge of the seat. Journal portions integrally associated with the cover 14 are mounted in the bearings 15 so that it is possible to swing the cover back as shown in Figure 2 or forwardly onto the blade seat as shown in Figure 1.

The rear edge of the blade seat is provided with three cutouts or recesses, one thereof denoted by the reference numeral 16 being centrally disposed and being substantially square. The recesses 17 are also substantially square but are smaller than the recess 16 and are symmetrically near opposite ends of the rear edge. Downwardly depending fingers 18 associated with the hinged or pivoted edge of the cover 14 are so arranged as to pass through the recesses 17 when the cover is swung closed.

In Figure 3 I have illustrated one form of spring arrangement wherein a single plate or element of spring steel 19 is attached, as by soldering or welding, to the under-surface of the seat 11. Only the forward portion of the plate 19 is attached to the seat 11, and the rear portion is formed with projections functioning as the springs proper. Thus, two rearwardly disposed projections 20 are so arranged as to underlie the recesses 17, and two rearwardly arranged and juxtaposed projections 21 are arranged to underlie the opposite sides of the recess 16. The projections 21 define a substantially rectangular recess 22 between them, this recess being in substantial registry with the recess 16. It will be pointed out at this time that the projections 21 act in unison, the recess 22 being provided to permit the element acted upon to extend upwardly therethrough.

In Figure 4, wherein the operation of one of the spring projections 20 is illustrated, the full line representation of the cover 14 shows the finger 18 in the position it assumes when it has passed through the recess 17 and has just commenced contact with the projection 20. Further closure of the cover will flex the projection 20 downwardly, but continued closure will cause the finger 18 to pass the dead center position, and the projection 20 will thereupon resume the position shown in Figure 4 and snap the cover 14 into the closed position shown in dot and dash lines. Similarly, in re-opening the cover, the initial movement will flex the projection 20 downwardly, but after the dead center position has been reached, the return of the projection 20 to its normal position will snap the cover into substantially opened position.

Referring for the moment to Figure 6, it will be noted that the seat support or platform 13 is provided with a pivotally mounted element having a rear portion or manipulable tab 23 and a forward portion or head 24. This element is pivoted in the rear portion

of the support 13, and I have illustratively shown a pivot axis or spindle 25 arranged in the rear portion of the support. The pivotally mounted element may swing from the forward position of Figure 6 to a rearward position, this rearward movement being achieved by pressing upon the tab 23.

It will be noted that the head 24 is formed upon a reduced portion 26, and the substantially transverse shoulders 27 immediately to the rear of this reduced portion are to be noted, as it is these shoulders which cooperate with the spring projections 21.

When the support 13 is associated with the holder, bolts 28 or the like may be employed for passage through the seat 11 and the plate 19 into threaded openings 29 in the support 13. In assembled position, the shoulders 27 underlie and contact with the projections 21, the reduced portion 26 passes through the recesses 22 and 16, and the head 24 positions itself above the rear portion of the blade seat 11.

In Figure 5, the tab 23 is shown in full lines in its forwardly pressed position, and accordingly, the head 24 is rearwardly disposed, and it will be noted that the rearward movement is checked by the cover 14. When the cover is closed, it will bear against the head 24 urging the latter forwardly. This will cause the shoulders 27 to bear upwardly against the spring projections 21 and flex these projections upwardly. After the dead center position has been reached, however, the projections 21 will resume their normal positions as shown in Figure 5, and will snap the pivoted element into its other extreme position illustrated in dot and dash lines in Figure 5. In this other extreme position, the tab 23 is rearwardly disposed, and the head 24 lies forwardly and is designed to bear against the rear reinforced portion 30 of a blade 31.

This pressure of the head 24 upon the blade 31 will cause the latter to position itself properly against the usual stops 32 provided upon the blade seat, and the razor is then in condition for use. When its employment has been completed, the tab 23 is pressed upon by the thumb or other finger of the user, and this will have the following effect. The spring 21 will commence to flex, offering slight resistance to the pressure upon the tab 23. The head 24 will presently encounter the inside surface of the closed cover and will initiate the opening of the latter. After this cover opening has been effected past the dead center position of the springs 20, the cover will snap back by itself as previously described. And after the dead center position of the springs 21 has been passed, the pivoted element which carries the head 24 will snap back into the full line position of Figure 5.

The opposite operation is of a similar character. Pressure upon the cover 14, to close the latter, will not only commence to flex the

5 springs 20 but will also urge the head 24 forwardly. After the dead center position of the springs 21 has been passed, the head 24 will snap forwardly against the blade 31. And after the dead center positions of the springs 20 have been passed, the cover will snap closed.

10 In Figure 7 I have illustrated a modified form wherein the springs 20 have been dispensed with. In this form, the head 24' is provided with a slightly increased length and a forwardly disposed resilient tip 33. Also, the cover 14' is provided with an inward projection or lug 34. The lug 34 is so positioned and arranged with respect to the tip 33, that when the cover is in fully closed position, as shown in dot and dash lines in Figure 7, the lug 34 will yieldably catch upon the tip 33. Accordingly, an extremely simple yet efficient 15 device is provided. Its operation is substantially like the operation previously described. As the cover is closed, the head 24' is urged forwardly and will presently snap into its foremost position by virtue of the action of the springs 21'. A continued closing of the 20 cover will presently cause the lug 34 to snap over and engage with the tip 33, and the razor will then be in condition for use. When it is desired to open the cover, and remove the 25 blade, pressure is exerted upon the tab 23' and this will not only release the pressure upon the blade but will also release the lug 34. And furthermore, it will open the cover by virtue of the pressure upon the inner surface 30 thereof by the head 24'.

It will be obvious that many changes in the details herein described and illustrated for the purpose of explaining the nature of my invention may be made by those skilled 40 in the art without departing from the spirit and scope of the invention as expressed in the appended claims. It is therefore intended that these details be interpreted as illustrative and not in a limiting sense.

45 Having thus described my invention and illustrated its use, what I claim as new and desire to secure by Letters Patent is—

50 1. In a safety razor holder which includes a blade seat and a pivoted cover therefor, spring means for yieldably retaining the cover closed, means for pressing a blade forward along said seat; said last named means including an element movable against or 55 away from the blade; and spring means for yieldably retaining said element in one or the other of said positions.

60 2. In a safety razor holder which includes a blade seat and a pivoted cover therefor, spring means for yieldably retaining the cover closed, means for pressing a blade forward along said seat; said last named means including a shouldered element movable against or away from the blade; and spring means 65 engaging said shoulder for yieldably retain-

ing said element in one or other of said positions.

3. In a safety razor holder which includes a blade seat and a pivoted cover therefor, means for yieldably retaining the cover closed 70 and also pressing a blade forward along said seat, said means including a spring; said means including an element independent of the cover and movable against or away from the blade and so positionally mounted with 75 respect to the cover that when it is moved away from the blade it will encounter the inside of the closed cover and initiate opening of the latter.

4. In a safety razor holder which includes a blade seat and a pivoted cover therefor, means for yieldably retaining the cover closed 80 and also pressing a blade forward along said seat, said means including a spring; said means including an element independent of the cover and movable against or away from the blade and so positionally mounted with 85 respect to the cover that when it is moved away from the blade it will encounter the inside of the closed cover and initiate opening 90 of the latter; said element being formed with a tab whose manipulation effects said movement.

5. In a safety razor holder which includes a blade seat and a pivoted cover therefor, 95 spring means for yieldably retaining the cover closed, means for pressing a blade forward along said seat; said last named means including an element independent of the cover and movable against or away from the blade; 100 spring means for yieldably retaining said element in one or the other of said positions; and said element being so positionally mounted with respect to the cover that the latter 105 will encounter it as the cover is closed to initiate the movement of said element toward the blade.

6. In a safety razor holder which includes a blade seat adapted to receive a blade thereon and a pivoted cover therefor, spring means 110 for yieldably retaining the cover fully closed or substantially open, and a manually operable element engaging the closed cover for initiating the opening thereof; said element being movable toward or away from the rear edge of the blade, and spring means for retaining it in one or the other of said positions.

7. In a safety razor holder which includes a blade seat adapted to receive a blade thereon and a pivoted cover therefor, spring means 120 for yieldably retaining the cover fully closed or substantially open, and a manually operable element engaging the closed cover for initiating the opening thereof; said element being movable against or away from the blade; spring means for yieldably retaining it in one or the other of said positions; and a manually operable tab for initiating the 125

movement of said element away from the blade.

8. In a safety razor holder which includes a blade seat adapted to receive a blade and a pivoted cover therefor, spring means for yieldably retaining the cover fully closed or substantially open, an element independent of the cover and movable against or away from a blade; spring means for yieldably retaining the element in one or the other of said positions; said element being so positionally mounted with respect to the cover that the latter in closing will encounter the element and initiate its forward movement while the element in its rearward movement will encounter and initiate a re-opening of the closed cover.

9. In a safety razor holder which includes a blade seat adapted to receive a blade and a pivoted cover therefor, spring means for yieldably retaining the cover fully closed or substantially open, an element independent of the cover and movable against or away from a blade; spring means for yieldably retaining the element in one or the other of said positions; said element being so positionally mounted with respect to the cover that in its movement away from the blade it will encounter the closed cover to initiate re-opening of the latter; and a manually operable tab for initiating said last-mentioned movement of the element.

10. In a device of the character described, in combination, a blade seat adapted to receive a blade thereon, a pivoted cover therefor, means movable into contact with the cover when the cover is closed for moving the cover to open position, said means comprising a movable element independent of the cover and so mounted with respect to the latter that, as the cover is moved from open to closed position, the cover will engage said element and move it into contact with the blade positioned on the seat to advance said blade along the seat.

11. In a device of the character described, in combination, a blade seat adapted to receive a blade thereon, a pivoted cover therefor, and an element movable in one direction into engagement with the blade on the seat and in the opposite direction into engagement with the cover to move the cover to open position, whereby said element when moved in the first mentioned direction will move the blade along the seat and when moved in the opposite direction will move the cover to open position and also release the blade.

12. In a device of the character described, in combination, a blade seat adapted to receive a blade thereon, a pivoted cover therefor, and an element movable in one direction into engagement with the blade on the seat and in the opposite direction into engagement with the cover to move the cover to

open position, whereby said element when moved in the first mentioned direction will move the blade along the seat and when moved in the opposite direction will move the cover to open position and also release the blade, and means for yieldably maintaining said element in one or the other of opposite positions to which it is movable.

13. In a device of the character described, in combination, a blade seat, a cover movable toward or from the blade seat to engage a blade thereon, and means for engaging a blade on the seat and moving it along the seat, said means including an element independent of the cover and engageable by the cover as the latter is moved to closed position to cause said element to engage and move the blade along its seat.

14. In a device of the character described, in combination, a blade seat adapted to receive a blade, a cover movable toward or from the blade seat to engage a blade thereon, and an element independent of the cover and positioned in the path of movement of the cover to closed position and movable into engagement with a blade on the seat, to cause said blade to advance along the seat as the cover is moved to closed position.

15. In a device of the character described, in combination, a blade seat adapted to receive a blade thereon, a pivoted cover therefor movable to a position closed on the seat or to a position away from the seat, an element pivoted to the seat and having a portion thereof positioned between the cover and the seat, whereby as the cover is moved to closed position said portion will be engaged by the cover and moved from one position to a position in engagement with a blade on the seat to advance it along the seat, and means for maintaining the cover and said element in one or the other of these positions.

16. In a device of the character described, in combination, a blade seat, a pivoted cover therefor movable from open position to closed position on the seat, an element pivoted to the seat and having a portion thereof positioned between the cover and the seat, whereby as the cover is moved to closed position said portion will be engaged by the cover and moved from one position to a position in engagement with a blade on the seat to advance it along the seat, and means for maintaining the cover and said element in one or the other of these positions, said means including a double acting spring.

17. In a safety razor holder which includes a blade seat adapted to receive a blade and a pivoted cover therefor, a pivoted element independent of the cover for pressing the blade forwardly along said seat, and a spring means cooperable simultaneously with said cover and said element to yieldably hold the cover in closed position and the element forwardly.

18. In a safety razor holder which includes a blade seat adapted to receive a blade and a pivoted cover therefor, a pivoted element independent of the cover for pressing the blade 5 forwardly along said seat, and a spring means cooperable simultaneously with said cover and said element to yieldably hold the cover in closed position and the element forwardly, said cover having a finger and said 10 element having a shoulder for engaging with said spring means.

19. In a safety razor holder which includes a blade seat adapted to receive a blade and a pivoted cover therefor, a pivoted element independent of the cover for pressing the blade forwardly along said seat, and a spring means cooperable simultaneously with said cover and said element to yieldably hold the cover in closed position and the element 15 forwardly, said element being so mounted between the cover and the blade seat that the cover in closing will encounter said element and pivot the latter forwardly.

In witness whereof I have signed and 25 sealed this specification.

GODFREY DALKOWITZ.
